MODULATION SYSTEM

Joachim Steinmetz, Berlin-Tempelhof, Germany,
assignor to C. Lorenz Aktiengesellschaft, Berlin-Tempelhof, Germany, a company

Application July 22, 1939, Serial No. 285,839
In Germany July 26, 1938

1 Claim. (Cl. 179—171.5)

Ultra-short wave transmitters comprising a control stage and a modulator stage have the disadvantage that the anodal retroaction affects the frequency of the control transmitter, thus causing this frequency to fluctuate. Therefore, electronic screen grid tubes have been employed in the main transmitter in order to reduce the anodal retroaction, and the screen grid has been earthed. In the case of ultra-short waves, however, the line that extends from the screen grid to earth constitutes a considerable inductance. As a result there is a retroaction from the screen grid on the control grid. Such retroaction has the same drawbacks as an anodal retroaction because in this case too the control frequency undergoes a detrimental variation.

The high frequency relationships are represented in the drawing, in which

Fig. 1 is a diagrammatic representation of the essential features of modulator stages as provided by the invention, Fig. 2 is a diagram that serves to explain the idea of the invention.

The control frequency, that is, the frequency arriving from the control transmitter T, is conveyed to the control grid G of a pentode of which the suppressor is not shown since it is immaterial to the invention, as indicated in Fig. 1. The modulation current from source M is applied to the screen grid SG. Included in the anode circuit is a Lecher line L which serves for tuning. The interelectrode capacities are represented as condensers shown in dotted lines. From Fig. 2 it will be seen that the interelectrode capacities may be thought to be comprised in a bridge connection. The points 1, 2 have a mutual phase difference of 180 degrees with respect to ground and may be considered as the feeding points.

The invention now consists in so balancing the two arms of such bridge connection that the control frequency shall not be affected. This is attained by balancing the two interelectrode capacities C_{AG} and C_{SGG} , that is, the capacities between anode A and control grid G on the one hand, and between screen grid SG and grid G on the other hand. Capacity C_{SGG} is known to be greater than capacity C_{AG} .

In accordance with the invention a capacity C_x is connected in parallel with the grid-anode capacity C_{AG} and this capacity C_x is made so great that the total current flowing through C_{AG} and C_x equals the current through C_{SGG} , the bridge thus being balanced. The control grid G on the one hand and ground on the other hand constitute the two diagonally opposite corners of the bridge between which corners there is zero potential difference under balance conditions. The novel arrangement acts perfectly to compensate the screen grid retroaction so that the control grid will not be affected to any extent.

What is claimed is:

An ultra-short wave modulating arrangement comprising a tube having a cathode, an anode, a screen grid, and a control grid, a plate impedance connected between said anode and ground, screen grid grounding connections having inherent impedance joining said screen grid to ground, a carrier frequency source connected to apply a carrier frequency potential between ground and said control grid, a source of signaling potential connected between the screen grid and ground whereby an oppositely phased signaling-frequency potential is established between said anode and ground, and a condenser connected between said anode and said control grid whereby said condenser and the inherent capacity between said anode and control grid in parallel constitute a first arm of a bridge, of which a second arm is constituted by the inherent capacity between said screen grid and said control grid and of which the remaining two arms are constituted by said plate impedance to ground and said inherent impedance of the screen grid grounding connections respectively, said first and second arms being connected in series between said anode and said screen grid, and said condenser having a value such that the resultant voltage developed between said anode and said screen grid due to said two signal frequency potentials causes equal currents to flow through said first and second arms.

JOACHIM STEINMETZ.
